COCKING MECHANISM

William Summerbell, Watervliet, N. Y.

Application May 16, 1941, Serial No. 393,764

3 Claims. (Cl. 89—24)

(Granted under the act of March 3, 1883, as
amended April 30, 1928; 370 O. G. 757)

The invention described herein may be manufactured and used by or for the Government for governmental purposes, without the payment to me of any royalty thereon.

This invention relates to a cocking mechanism for a gun of the type having a vertically sliding breech block. The firing mechanism employed forms the subject matter of my copending application, Serial No. 274,987 and the cocking mechanism represents an improvement over that shown in that application.

It is the object of this invention to provide a cocking mechanism which is automatically actuated by the operation of the breech block and which will be simple and reliable in its functioning.

It is a further object of my invention to simplify the assembly and maintenance of the cocking mechanism.

The specific nature of the invention as well as other objects and advantages thereof will clearly appear from a description of a preferred embodiment as shown in the accompanying drawing in which:

Figure 1 is a side elevation, partly in section of the breech mechanism with the breech in closed position.

Figure 2 is an end elevation corresponding to Figure 1.

Figure 3 is a side elevation, partly in section with the breech in open position.

Figure 4 is a top plan view of the cocking mechanism with the breech ring shown in section.

Figures 5 and 6 are, respectively, side and end elevations, of the cocking lever.

Figure 7 is an enlarged sectional view of portions of the firing and cocking mechanism in the breech block taken on the line 7—7 of Fig. 1. The parts are in cocked position.

Figure 8 is an enlarged sectional plan view of a portion of the breech ring including the cocking pin and a portion of the cocking lever.

Referring to the drawing by characters of reference there is shown a breech ring 1, having an opening for a vertically sliding breech block 2, the mechanism for operating the block being omitted. The breech block is formed with a bore 3 which houses a firing mechanism 4 of the type referred to in applicant's copending application, Serial No. 274,987. The firing mechanism is provided with a laterally extending lug 5 for engagement with the cocking device which is the subject of this application. The firing

mechanism is further provided with means for engaging a sear 7 provided to maintain the firing mechanism in cocked position until released by the gunner.

5 The cocking lever 8 (Figs. 5 and 6) is formed with a cylindrical shaft portion 9 having two arms extending therefrom. The upwardly extending arm 10 is flush on its outer surface with the end of the cylindrical portion 9 and is provided on its upper curved end with a laterally extending lug 11 for a purpose as will hereinafter appear. Between the cylindrical portion 9 and the downwardly extending arm 12 is a spring engaging web 13. The arm is provided on its 10 lower end with a laterally extending lug 14. A portion 15 of the cylindrical portion 9 extends beyond the arm 12 to provide a trunnion for the cocking lever.

Milled cuts are provided in the faces of the 20 breech block for lightness and to accommodate the cocking lever, the slot 16 is milled to such a depth that it intersects the bore 3 in which the firing mechanism is housed and a lateral bore 17 is formed in the side of the block to a depth equal

25 to the length of the cylindrical portion 9. Below this lateral bore an opening, roughly the shape of a segment of a cylinder, is milled into the block intersecting the slot 16 and the bore 17 and deep enough to accommodate the downwardly extending arm 12 of the cocking lever.

The side face of the block has been milled back as best shown in Figure 3 to provide guiding surfaces and to allow the upwardly extending arm to be rotated about the cylindrical shaft 30 without interfering with the operation of the block. Other cuts have been made to reduce weight as far as practicable without dangerously reducing strength. A hole 18 is bored into the block from the front to accommodate a spring 19

40 and plunger 20.

The cocking lever may be assembled to the block by inserting the spring and plunger into the bore provided for them and while holding them in retracted position inserting the cocking lever from the side, in which position the lug 14 will extend into the bore 3 in position to engage with the lug 5 on the firing device as shown in Fig. 7. Upon release the plunger 20 will 45 engage the web 13 and bias the lower end of the cocking lever to forward position. The cocking lever is retained in the block by engagement with the side wall of the block receiving opening in the breech ring.

55 The rear face of the breech ring is provided

with a bore 21 to accommodate a pin 22 and a retaining screw 23. A cylindrical segment is removed from a portion of the end of the pin leaving a reduced portion 24 of the pin which extends through that portion of the bore intersecting the breech block receiving opening in the breech ring and is provided with a cam surface to engage the lug 11 on the cocking lever, as shown in Fig. 8. The lower edge of 24 is undercut slightly to provide a cam surface to engage the upper surface of the lug 11 and urge it forward preventing catching when the block is initially inserted in the breech ring.

The breech block operating mechanism functions in a known manner in that the breech block is drawn downwards against spring pressure after firing and upon striking limiting stops, not shown, tends to return but is engaged in a known manner by the extractors, not shown, to prevent such return until released by insertion of a new round. In its downward movement the block overtravels slightly the position in which it is ultimately retained by the extractors. This overtravel is made use of in connection with the cocking mechanism to insure positive shifting of the load of the firing spring from the cocking lever to the sear mechanism.

As the breech mechanism is drawn downwardly, the arm 10 of the cocking lever engages the forwardly facing shoulder formed by the breech block receiving opening in the breech ring. Near the completion of the downward travel of the block the lug 11 engages the cam end of pin 22 and the firing mechanism 4 is completely cocked. As the block rises to the point of engagement with the extractors, the lug is disengaged from the pin and the firing mechanism moves forward sufficiently to allow the lug 6 to seat upon the sear 7. The positive shifting of the load from cocking lever to sear reduces the wear upon the cocking lever and the face of the breech block with which it engages and speeds the returning action of the block by reducing drag.

Elements of the firing mechanism which are shown but are not directly concerned with the inventive subject matter of this application include a trigger 25 rotatably mounted in the breech ring and having attached thereto a tripper 26 which engages a cam 27 on the sear 7 to move the sear laterally for releasing the firing mechanism. The tripper is provided with a depending arm 28 having a finger 29 extending across the front face of the block. When the

block is in closed position, the finger is clear to rotate under the corner of the block but in any other position of the block the finger is restrained by the front face of the block thus positively preventing movement of the trigger to fire the gun except when the block is fully closed. A spring 30 and plunger 31 are provided to bias the trigger to non-firing position.

It will be noted that should the sear break or fail to properly engage the firing pin the engagement of the lug 11 with the breech ring will gradually lower the firing pin to rest against the rebounding mechanism preventing protrusion of the firing pin and probable breakage as the block rises to closed position.

I claim:

1. In a gun having a breech block enclosing a firing mechanism and a breech ring in which said block is slidably mounted, a cocking mechanism comprising a lever journaled in the breech block, means on said lever engageable with said firing mechanism for cocking thereof, an arm on said lever extending beyond the limits of the breech block engaging the breech ring to swing the lever as the breech is opened, and camming means in said breech ring engaging the lever to further swing the lever and cock the firing mechanism as the breech opening movement is concluded.

2. In a gun having a breech block enclosing a firing mechanism and a breech ring in which said block is slidably mounted, a cocking mechanism comprising a lever journaled in the breech ring, an arm on the lever having means engageable with the firing mechanism for cocking thereof, a lever-engaging member mounted in the breech ring, and a second arm on the lever successively engageable with the breech ring and the lever-engaging member whereby the lever is operated to cock the firing mechanism as the breech is opened.

3. In a gun having a breech block enclosing a firing mechanism and a breech ring with an opening in which said block is slidably mounted, a cocking mechanism comprising a cocking lever journaled in the breech block and having means engageable with the firing mechanism for cocking thereof, cocking lever engaging means in the opening in the breech ring and an arm on the cocking lever having an end portion successively engageable with the wall of the opening in the breech ring and with said cocking lever engaging means as the block is operated to open the breech.

WILLIAM SUMMERBELL.
